Patented Oct. 14, 1975

237,161

BOAT LIFTING AND DOCKING DEVICE

Burdette R. Kramer, Rte. 2, New London, Minn. 56273

Filed Jan. 24, 1974, Ser. No. 436,085

Term of patent 14 years

Int. Cl. D12—05

U.S. Cl. D12—53

Fig. 1

Fig. 2

Fig. 3

Fig. 4

FIG. 1 is a right front perspective view of a boat lifting and docking device showing my new design;

FIG. 2 is a left front perspective view thereof;

FIG. 3 is a top plan view thereof;

FIG. 4 is a front elevational view thereof;

FIG. 5 is a right side elevational view thereof;

FIG. 6 is a left side elevational view thereof; and

FIG. 7 is a rear elevational view thereof.

I claim:

The ornamental design for a boat lifting and docking device, substantially as shown.
